FIG. 1.

FIG. 2.

FIG. 3.

FIG. 4.

UNITED STATES PATENT OFFICE.

GEORGE ALLEN, JR., OF NEW YORK, N. Y., ASSIGNOR TO GEORGE ALLEN & SON, A FIRM CONSISTING OF JANE ALLEN, WILLIAM ALLEN, AND GEORGE ALLEN, JR., ALL OF NEW YORK, N. Y.

BAFFLE-SLOT BLOCK.

Application filed June 16, 1927. Serial No. 199,160.

My invention relates to improvements in baffle slot blocks such as are used in a masonry wall to provide a slot for an inclined baffle. Such a structure is often seen 5 in boiler settings. The object of my invention is to produce a simple block which can be used to advantage in the customary brick wall and can be disposed in series upon both sides of the baffle so as to form an inclined 10 slot for the baffle and abutting wall and both sides of it.

My improved block is adapted for use as stated with a brick wall and to this end it is made of a height representing a multiple of 15 the thickness of an ordinary commercial brick, that is to say, it will be the height of one brick, two bricks, or more as desired, and thus it is very easily built in with the brick wall and forms an easy and perfect 20 bond. In building the wall to abut with an inclined baffle or similarly inclined member, it is difficult to break and shape the brick to abut properly with the baffle and provide a slot therefor, and it is also difficult to make a 25 neat and suitable job of the work. My invention comprises a block generally rectangular but having on one side an inclined face from which rises an outwardly projecting tongue, thus dividing the face into two 30 parts, or in other words forming inclined recesses at the two inner corners of the block. By shaping the block in this manner, it is very easy to apply it to a baffle and to a wall, and it can be applied on either side of a 35 baffle or the like, or it can be applied on either the right or left wall of a baffle with the greatest facility.

It is also easy to produce an inclined baffle slot in which the baffles may be on both sides 40 of the block when desired. By the construction shown, the block when used one side up fits against the one side of the inclined baffle, and when used the other side up fits against the opposite side of the baffle, and when applied to the left wall of a baffle, the slot will 45 be on one side of the block, and when the block is applied to the right side of the baffle, the baffle slot will be on the left side of the block, all of which will be better understood 50 from the description which follows. It will also be understood that while I refer to a block useful in forming an inclined baffle slot, it can be used to advantage in completing a wall against any inclined member

and to form a slot in which the member can 55 expand.

Reference is to be had to the accompanying drawings in which similar reference characters represent the corresponding parts in all views.

Figure 1 is a sectional elevation of a wall 60 with a baffle slot therein and with the baffle in place in the slot.

Figure 2 is a broken enlarged perspective view showing opposed blocks with baffles on 65 both sides of the blocks and entering the slots formed between them.

Figure 3 is a perspective view of the block itself, and

Figure 4 is a perspective view of two meeting blocks and with a baffle and adjacent wall shown by dotted lines.

The block 10 is of any suitable refractory material and one end portion is of rectangular shape, but the opposite end or side has an inclined face 11 from the middle portion of which rises a protruding tongue 12. The tongue is preferably of the same height as the block, and this arrangement forms two notches or recesses at the inner block corners, 75 the walls of which are inclined as shown. The block is made preferably of the height of two commercial bricks, as this is found to be the more convenient size to use, and in any event it should be of a height representing 80 a multiple of the thickness of the brick, that is to say, it should be the height of one brick, two bricks, or more. The object of this is to enable it to be laid in a masonry wall and for the brick courses to come into 85 the right height against the block, thus making it easy to lay them and also causing 90 a better bond.

It will be seen that when the two blocks are laid in opposition, for example as in 95 Figure 4, with one block having the long part of the tongue upward, and the opposite block having the long part of the tongue downward, or in other words when the blocks are not the same side up, the opposed 100 tongues will meet and an inclined slot will be formed between the blocks, and on each side of the tongues 12, so that an inclined baffle 13 can be placed in one of the slots, and the other slot closed as by a wall 14, or the 105 blocks may be laid in the center wall with baffles 13 or similar parts in both slots, that is on both sides of the block course. There-

- fore, it will be understood that in laying a wall to provide for a baffle as 13, the blocks on one side of the baffle are the other side up from those on the opposite side of the baffle.
- 5 Thus it will be seen that the wall can be laid up snugly against the baffle on both sides, making a perfect joint and also a perfect slot and effecting a tight closure which will in no wise interfere with the free expansion 10 of the baffle. It will likewise be evident that the blocks can be readily laid in the masonry wall, bonded like the bricks of the wall and applied to either side of a wall, so that baffles 13 or other inclined members can enter the slots formed as stated.

Thus it will be seen that by my simple form of block, I am enabled to lay a wall more neatly and better than by the usual practice, and at far less cost. Attention is 20 further called to the fact that the tongue 12 is preferably of the same height as the body of the block, and that its outer face 12' is preferably parallel with the opposite face of the block so that when opposed blocks are 25 arranged as shown in the drawings with their tongues meeting, they will form a tight closure and the result will be two inclined slots on the sides of the meeting tongues.

I claim:

- 30 1. A masonry block having a rectangular cross-section, and its top and bottom surfaces parallel to each other, one end face of said block being a plane surface; the other end face being inclined, and a tongue projecting from said inclined face.

2. A masonry block having a rectangular cross-section and its top and bottom surfaces

parallel to each other, the distance between said surfaces being a multiple of the thickness of a commercial brick, one end face of 40 said block being a plane surface, the other end face being inclined, and a tongue projecting from said inclined face.

3. A masonry brick having a rectangular cross-section and its top and bottom surfaces 45 parallel to each other, one end face of said block being a plane surface disposed perpendicularly to said top and bottom surfaces, the other end surface being inclined to said top and bottom surfaces, and a tongue projecting from said inclined face.

4. A masonry brick having a rectangular cross-section and its top and bottom surfaces parallel to each other, one end face of 50 said block being a plane surface, the other end face being inclined, and a tongue projecting from said inclined face, said tongue being disposed medially of the sides of the block and having its end surface perpendicular to said top and bottom surfaces.

5. A furnace wall comprising a plurality of bricks, each of said bricks having top and bottom surfaces in parallel relation, one end of each brick being inclined and having a tongue projecting therefrom, the inclined 60 faces of horizontally aligned bricks being parallel and held in spaced relation by said tongues, and a baffle wall adapted to be supported in the space between said inclined faces.

In testimony whereof, I have signed my name to this specification this 10th day of June 1927.

GEORGE ALLEN JR.
